UNITED STATES PATENT OFFICE.

VICTOR W. PAGÉ, OF KEW GARDENS, NEW YORK.

CAM-FOLLOWER GUIDE.

Application filed February 2, 1922. Serial No. 533,730.

To all whom it may concern:

Be it known that I, VICTOR W. PAGÉ, a citizen of the United States, and a resident of the city of New York, Kew Gardens, 5 borough of Queens, in the county of Queens and State of New York, have invented a new and Improved Cam-Follower Guide, of which the following is a full, clear, and exact description.

10 The present invention relates to new and useful improvements in valve mechanisms of internal combustion motors, and it pertains more particularly to a cam follower guide.

15 It is one of the primary objects of the invention to prevent a cam follower from pumping oil through the guide during the operation of the follower to operate the valves.

20 It is a further object of the invention to provide means for returning the oil to the source of supply as it is pumped by the action of the cam followers.

25 With the above and other objects in view, reference is had to the accompanying drawings, in which—

Figure 1 is a vertical sectional view taken transversely of the cam shaft housing, and

30 Fig. 2 is a vertical sectional view taken at right angles to Fig. 1, or longitudinally of the cam shaft housing.

Referring more particularly to the drawings, the reference character 5 designates a cam shaft, and 6 designates the cam shaft housing. Mounted upon the upper face of the cam shaft housing 6, are guides 7 adapted to form bearings for the cam followers of a valve mechanism, the remaining portion of which is not shown since it forms 35 no part of the present invention. As more clearly shown in Fig. 2, these cam followers or guides 7 are preferably arranged in pairs and are secured to the cam shaft housing 6 by means of cap screws or the like 8. Each 40 of the cam follower guides is provided with a central passage 9, and said central passage 9 forms the bearing for the cam followers 10.

The reference character 12 designates an 45 annular channel formed in the side walls of the central passage 9 at approximately the center of the cam follower guides. Leading from each of these annular channels 12 is a passage 13, and said passage 13 communicates with an enlarged chamber 14, which 50 in turn communicates with the interior of the cam shaft housing 6.

by means of an opening 15 therein. The upper end of each of the cam follower guides is provided with a stuffing box recess 19 and said recess is internally screw-threaded to receive a packing gland 20, by means of which packing may be compressed within the recess 19.

Each of the cam followers 10 is provided with a cut-out portion 21, and each of the cam follower guides 7 is provided with an internally screw-threaded recess 22 adapted to receive a screw 23. The inner end of each of these screws 23 is reduced as indicated by the reference character 24, and each of the screws is adapted to have its reduced end 24 positioned within the cut-out portion 21 of its respective cam follower in order to prevent rotary movement of the cam follower within its cam follower guide 7.

Mounted in each of the cam followers 10 is a pin 25 having a head 26. The pin is shorter than the cam follower 10, and interposed between its lower end and the bottom of the cam follower 10, is a spring 27, the lower end of which cam follower is provided with an oil opening 28.

The device operates in the following manner:

As the cam shaft is rotated to operate the cam follower, the lubricant within the cam shaft housing is splashed into contact with the cam follower guide. In the ordinary structure of such devices, the reciprocating movement of the cam follower tends to pump the lubricant through the cam follower guide until the same flows over the upper edge of the cam follower, thus causing a constant waste of lubricant as well as a steady fouling of the exterior of the valve mechanism. In the present construction, however, it is apparent that as the oil is pumped upwardly around the cam follower during its reciprocating movement, the same will be collected within the annular channels 12 and will be returned by means of the passages 13, enlarged chamber 14, and opening 15 to the cam shaft housing 6, thus preventing the lubricant from pumping upwardly around the cam follower and discharging through the packing box or around the upper end of said cam follower.

From the foregoing it is apparent that the present invention provides a new and improved mechanism, the use of which prevents cam followers from pumping lubricant from the interior of the cam shaft hous-

ing to the exterior thereof, thus saving an appreciable quantity of lubricant as well as preventing the lubricant being pumped on to the several motor parts by the reciprocating action of the cam followers.

What is claimed is:

1. In combination with a cam shaft housing, a plurality of cam follower guides, each having a longitudinal passage to receive the cam follower, and each provided with an annular passage in the side walls of the cam follower passage, passages extending from said annular passages to a passage in the cam shaft housing opening into the interior thereof, whereby lubricant pumped by the cam follower will be collected and returned to the cam shaft housing.

2. A cam shaft follower guide adapted to be mounted upon a cam shaft housing and having a longitudinal passage for the re-

ception of a cam follower, said guide being formed with an annular passage adapted to collect lubricant pumped by the cam follower, said cam follower guide also being formed with an angularly disposed passage 25 whereby the lubricant collected in said annular passage is returned to the cam shaft housing.

3. In a cam follower mechanism, a cam shaft housing, a cam follower guide carried thereby, an annular channel formed in the cam follower guide adapted to collect lubricant pumped by the cam follower, and a channel formed in said cam follower and extending longitudinally 30 thereof from a point above the annular channel to the lower end of said cam follower whereby lubricant in the annular channel will be conveyed to the cam shaft housing.
